I. J. AMATO

SPARK INTENSIFIER

Filed Dec. 22, 1919

Inventor.
I. J. Amato.

By *Lacy & Lacy,*
No. 11475.

UNITED STATES PATENT OFFICE.

IRVING J. AMATO, OF PITTSFIELD, MASSACHUSETTS, ASSIGNOR OF ONE-HALF TO
RAYMOND D. TUFTS, OF PITTSFIELD, MASSACHUSETTS.

SPARK INTENSIFIER.

Application filed December 22, 1919. Serial No. 346,577.

To all whom it may concern:

Be it known that I, IRVING J. AMATO, a citizen of the United States, residing at Pittsfield, in the county of Berkshire and 5 State of Massachusetts, have invented certain new and useful Improvements in Spark Intensifiers, of which the following is a specification.

This invention relates to improvements in 10 spark intensifiers especially adapted for use on the spark plugs of internal combustion engines.

An important object of this invention is to 15 provide a spark intensifier for spark plugs having novel means for forming a spark gap by arranging one end of the feed cable in spaced relation to the post or tongue whereby the terminal of the cable is caused to function as one side of the gap.

20 A further object of this invention is to provide a spark intensifier for spark plugs having novel means whereby the same may be rapidly and securely attached to one end portion of a feed cable without the necessity of entirely detaching the feed cable from the motor.

25 A further object of the invention is to provide a spark intensifier for spark plugs having novel means whereby the spark created upon jumping the gap may be readily viewed.

30 A further object of the invention is to provide a spark intensifier for spark plugs which is efficient and desirable in use and 35 which may be manufactured and sold at an extremely low cost.

Other objects and advantages of the invention will be apparent during the course of the following description.

40 In the accompanying drawing forming a part of this application and in which like numerals are employed throughout the same to designate like parts:

45 Figure 1 is a side elevation of the improved spark intensifier applied,

Figure 2 is a perspective of the same,

Figure 3 is a central vertical longitudinal section through the same, and

50 Figure 4 is a vertical transverse section taken on the line 4—4 of Figure 3.

In the drawing wherein for the purpose of illustration is shown a preferred embodiment of the invention, the numeral 5 generally designates an internal combustion en-

gine to which is attached a spark plug 6 of any desired type. The improved spark intensifier generally designated by the numeral 7 is formed from a single blank of metal which may be of copper or any material having the qualities necessary to conduct electric current. As illustrated in Figure 2, the blank of metal 7 is of elongated formation and has one end portion arranged in cylindrical formation for forming an attaching device 8 for a feed cable 9. The cylindrical attaching device thus formed is provided with an annular groove 10 within which is received a split ring 11 adapted for securely retaining the attaching device 8 in engagement with the cable. The annular groove 10 is provided by pressing the cylindrical attaching device inwardly thereby forming an interiorly arranged annular shoulder 12 which firmly grips the cable for locking the same within the cylindrical attaching device. Therefore the annular groove serves a dual function which is first to receive the locking ring 11 and secondly to form the annular shoulder 12 which firmly grips the cable and thereby locks the forward end of the cable within the cylindrical attaching portion 8 without the necessity of employing solder or other fastening means as is customary in devices of this character. The cable 9, of course, is provided with the usual insulation and conductor wire 13 which has connection with a source of electrical energy such as a storage battery or magneto.

55 A tongue 14 is struck up from the bottom or under side of the cylindrical attaching member 8 for forming a spark gap in cooperation with the forward end of the wire 13. The tongue or post 14 is tapered throughout its length and has its forward end pointed and arranged in spaced relation and approximately in longitudinal alinement with the cable wire 13 so as to form a gap over which the current must jump in order to reach the spark plug. It is a well-known fact that by interrupting the current during 60 its passage to the electrodes of the spark plugs, the current is intensified for creating a hotter spark at the sparking point of the spark plug.

65 It will be noted with reference to Figure 4 that the sides of the tapered tongue or post 14 are spaced a greater distance from the sides of the cylindrical body than the point

- of said tongue is spaced from the adjacent end of said wire 13. This precludes the possibility of the current jumping from the forward end of the wire 13 to the sides of the 5 cylindrical body. The tongue 14 is capable of manual adjustment with relation to the forward end of the wire 13 so that the spark gap may be varied at will according to circumstances.
10. The meeting edges of the cylindrical attaching body 8 are provided with semi-circular openings 15 which form a sight opening directly over the tongue 14 and the forward end of the wire 13 so that at any time 15 during the use of the device the spark jumping over the gap may be viewed. Also the opposed semi-circular openings 15 provide means whereby a small tool may be engaged with the struck up tongue 14 for adjusting the same with relation to the forward end 20 of the wire 13. The forward portion of the cylindrical attaching body 8 has its meeting edges overlapped, as indicated at 16, for strengthening and reinforcing the entire device.
25. The forward portion of the cylindrical attaching body 8 is provided with an extension 17 having a centrally arranged opening 18 adapted to receive the post or conductor 19 of the spark plug. A suitable 30 binding nut 20 is threaded on the post 19 and serves to securely attach the device to the spark plug.

With reference to the foregoing it will be noted that the improved spark intensifier 35 may be economically stamped from a single blank of metal and by reason of the fact that the same may be so manufactured, the device may be placed upon the market at an extremely low cost. Also it will be noted that 40 the device may be readily attached to the feed cable of the ignition system without the exercise of skill or without the necessity of soldering or screwing the cable in position. When it is desired to connect the cable to the 45 cylindrical attaching device 8 the forward end of the same is inserted within said cylindrical device and the split ring, which is preferably of spring metal, is received within the groove 10 so as to cause the annular shoulder 12 to firmly grip the cable. By this 50 construction the cable is securely held at its forward end portion within the cylindrical attaching device and is prevented from accidental displacement as result of vibration of 55 the motor.

As the device when applied is only of a slightly greater diameter than the cable, the possibility of short circuiting the system as the result of using the device is remote. In 60 addition to functioning as a spark intensifier, the device of course functions as a ter-

65 minal connecting device and displaces the terminal connectors now in general use.

Having thus described the invention, what is claimed as new is:

1. A spark intensifier including a cylindrical cable receiving body having an exterior annular groove forming an interior annular shoulder adapted for gripping the cable, a locking device seated in said groove 70 for contracting said body, and a post carried by said body.
2. A spark intensifier including a longitudinally split cylindrical body having an exterior annular groove forming an interior 75 annular shoulder adapted for gripping a feed cable, and a split ring arranged within said annular groove, said body being provided with a post.
3. A spark intensifier including a longitudinally split body having means for gripping a feed cable, the meeting edges of said body being provided with opposed openings forming a sight opening, said body being provided with a post.
4. A spark intensifier including a longitudinally split body having its meeting edges provided with semi-circular openings forming a sight opening, the meeting edges of said cylindrical body beyond said sight opening being overlapped for strengthening and reinforcing the body, said body being provided with a post.
5. A spark intensifier including a body having means at its rear end portion for securely gripping a feed cable, said body being provided with a tongue having a pointed end arranged in spaced relation to the forward end of said cable for forming a spark gap and in spaced relation to the sides of said body, said body being provided with a sight opening adjacent said tongue, and an extension carried by said body and adapted for engaging a spark plug.
6. The combination with a cylindrical body having its rear end portion provided with an annular groove thereby forming an interior shoulder, of a feed cable having its forward portion received within said body and gripped by said annular shoulder, a locking device arranged within said annular groove, a post arranged within said body and terminating in spaced relation to the forward end of said cable for cooperating with the cable in forming a spark gap, said body being provided with a sight opening, and an extension formed integral with the forward end of said body and having means for engaging a spark plug.
